UNITED STATES PATENT OFFICE

2,593,891

CONSTRUCTION OF PANELED WALLS FOR
BUILDINGSCyril Ernest Kenney, Portman Square, London,
EnglandApplication October 26, 1945, Serial No. 624,885
In Great Britain June 30, 1944

1 Claim. (Cl. 189—34)

1

This invention relates to the construction of panelled walls for buildings and particularly to external walls of this class.

It is the primary object of the invention to provide an improved method of making panelled structures, which is particularly applicable to the outside walls of buildings, as it enables a completely weather-tight joint between the panels to be readily obtained. The invention is not, however, limited to this particular use, as the improved form of joint is quite decorative and has wide application, internally as well as externally.

It is a further object of the invention to provide an improved form and construction of capping member which has been evolved primarily in order to enable artificial stone glass or analogous cast, pressed or moulded material to be utilised, at the same time avoiding the necessity of providing fixing means which are separate from the capping member, such, for instance, as screws or clips.

According to the invention a method of wall construction comprises securing adjacent edges of a pair of wall panels to a stanchion or like structural member, leaving a gap between the panels and then closing said gap by a capping member or an end-to-end series of capping members which engage the panels by tongue and groove joints, and which are slid endwise along the panel edges into position.

Moreover in a method of wall construction in which panel members are secured side by side to an upright stanchion or like structural member, according to the invention said panels are formed with adjacent edges which are spaced from one another and from said structural member, and a capping member is slid endwise along said edges to bridge the space between the panels, said capping member being formed in its two upright sides with grooves arranged to receive the said edges of the panels.

Preferably, the panels have marginal frames which are formed with flanges engaged by grooves along the corresponding edges of the capping member or members. The cavity behind the capping member or members is usually substantially filled with mastic cement to produce a water-tight joint across the edges of the panels. The structural member is preferably formed with a flange which enters a longitudinal groove in the capping member or members.

As a further feature of the invention a wall of a building comprises upright stanchions or like structural members spaced at intervals, panels extending between said structural mem-

2

bers and secured thereto, and capping members arranged to bridge the adjacent edges of the panels, said capping members being interengaged with the panels by tongue and groove joints. The structural members may be of T-shape in section, with the central flange extending towards the capping members, the central flange of the T-shape structural member conveniently entering a groove formed in a capping member corresponding with said structural member. The capping members may advantageously be made of artificial stone, glass, or other suitable material moulded or pressed to shape with grooves for engagement by tongues on the panels. The panels may have metal or other frames shaped in cross section with internal and external flanges, the internal flanges holding the material of the panels and the external flanges being in engagement with grooves in the capping members.

The invention is illustrated by way of example in the accompanying diagrammatic drawings in which:

Figure 1 is a side elevation of a partly assembled wall of a building;

Figure 2 is a fragmentary section taken on the line 2—2 of Figure 1 and drawn to an enlarged scale; and

Figure 3 is a view similar to Figure 2 but showing a conveniently modified construction for use at the corners of buildings.

In the preferred method of carrying the invention into effect for the construction of the walls of dwelling houses and like buildings, the walls are composed of a relatively large number of vertical stanchions placed at intervals of say three feet and firmly secured to a foundation. Two such stanchions are indicated at 10 and 11 in Figure 1 and have their lower ends respectively embedded in a foundation 12 as indicated at 13 and 14. The stanchions 10 and 11 are composed of steel rolled to a T-shape in cross section and will be seen more clearly in Figure 2, the transverse limb 15 of the section being arranged substantially parallel with the general plane of the wall while the central flange 16 is directed towards the exterior of the wall. The spaces between the stanchions are occupied by panels, three of which are shown in Figure 1 at 17, 18 and 19. In general these panels are built up with metal frames, the sheet material which is fitted within said frames being arranged in accordance with the function required to be performed by the particular section of wall concerned. Thus, 53 the panel 18 has a metal frame 20, the inwardly

facing surface of which is formed with three flanges 21, 22, and 23 arranged for the reception of a sheet 24 of opaque glass and a sheet 25 of material having good heat insulating properties. On the other hand the panel 17 is contained within a frame 25 which is fitted with a movable window frame 26, the glass of which is shown at 27; the window frame 26 is arranged to co-operate in the usual manner with flanges 28 and 29 upon the frame 25 so as to secure a reasonably weather-tight fit when the window is closed. As the window frame 26 does not extend to the bottom of the panel 17 the lower part of the latter is constituted by a section of wall material 30 conveniently of the same construction as the panel 18.

In the construction shown the vertical edges of the flanges are secured to the stanchions by sheet metal clips; thus as shown in Figure 2 the frame 20 of the panel 18 has a number of substantially U-shape clips, one of which is shown at 31, these conveniently being attached by screws or rivets as at 32. The opposite ends of the clips 31 are secured to the flange 16 of the stanchion 10 by nuts and bolts 33 which latter also serve for the attachment of the corresponding clips 34 belonging to the adjacent edge of the panel 17.

In order to produce a weather-tight joint between the panels, elongated capping members are provided, four of these being shown in Figure 1 at 35, 36, 37 and 38. These are moulded or pressed to shape and can conveniently be made of artificial stone, glass or like material so as to have a pleasing appearance and be substantially immune from deterioration by climatic conditions. The form of capping member shown in Figure 2 is made of glass and it appears externally as a heavy beading of substantially semi-circular shape in cross section. At its rear part it is formed with a longitudinal groove 39 which is arranged to fit over the outer part of the stanchion flange 16 while, at its two sides, it is formed with longitudinal grooves 40 and 41 respectively; these are arranged to slide over flanges 42 and 43 upon the frames 25 and 20, the capping members being slid endwise into position during the fitting of the panels as for instance is shown in the case of the capping member 36 in Figure 1. This produces an exceedingly neat appearance as the capping members completely cover the means used for securing the panels in position. After the capping members 35-38 are in place, the spaces 44 between the capping members (such as 35) and the inner limbs 15 of the stanchion are completely filled with a mastic cement or like composition which enters the groove 40 and 41 thus producing a completely water-tight seal and at the same time locking the parts securely together.

At the corner of the building the construction shown in Figure 3 can be used. A pair of T-section stanchions 50 and 51 are placed together with their respective central flanges 52 and 53 pointing in opposite directions. To the flange 52 the panels of one wall are secured, conveniently by L-shaped clips, one of which is seen at 53 holding in position a wall panel unit 54. On the other hand the adjoining wall panel unit 55 is attached to the other stanchion 51 by clips of U-shape, one of which is shown at 56. The stanchions 50 and 51 are enclosed by a capping member 57 which is of somewhat J-shape in cross section and which has an elongated groove at 58 for engagement by a flange 59 upon the frame of the

panel member 54, while along its opposite edge the capping member 57 has a groove 60 for engagement over a flange 61 upon the panel member 55. At its rear or inner part the capping member 57 has a groove 62 for the accommodation of the flange 53 while it has also a groove at 63 to receive the transverse limbs 64 and 65 of the stanchion members 50 and 51 respectively. After the capping members 57 have been slid into position the spaces 66 are filled with mastic cement or like composition in order to secure the parts together and produce the requisite weather-tightness. It may be desirable in some cases to make each of the capping members 57 in two parts which are arranged to abut together as shown in broken lines at 67, thus facilitating the manufacture of the capping members and also their transport and erection; the mastic cement within the spaces 66 adjacent the division 67 ensures that a weather-tight joint is obtained between the two parts of the capping member.

It will be understood that the arrangements which have been described are given merely by way of example and that various modifications may be made to suit requirements. The outside part of the capping members can be of any desired shape.

What I claim is:

In a wall of the class described, an upright stanchion, a pair of panel members extending laterally from either side of said stanchion, said stanchion being of T-shape in cross section with its transverse limb parallel with the panel members and its central limb between adjacent vertical panel edges, fastening clips securing the panel members to the central limb of the stanchion, leaving an intermediate space, flanges upon the adjacent vertical edges of the panel members disposed so that the edges of the flanges face the stanchion, a rod-like capping member having a deep groove extending vertically along each of its two sides and its rear, said capping member being mounted along the flanges of both said panels respectively, and the front edge of said stanchion central limb by slidale endwise movement so that the grooves receive the flanges and the capping member is held by the positive interlocking engagement of said flanges with the said deep grooves, and waterproof sealing material filling the intermediate space between the edges of the panel members and between the back of the capping member and the stanchion, to provide a waterproof seal between the capping member and the panel members.

CYRIL ERNEST KENNEY.
